UNITED STATES PATENT OFFICE.

WALTER L. MARR, OF FLINT, MICHIGAN.

LUBRICATING SYSTEM FOR MOTORS.

1,104,057.

Specification of Letters Patent. Patented July 21, 1914.

Application filed April 21, 1913. Serial No. 762,527.

To all whom it may concern:

Be it known that I, WALTER L. MARR, a citizen of the United States of America, residing at Flint, in the county of Genesee and 5 State of Michigan, have invented certain new and useful Improvements in Lubricating Systems for Motors, of which the following is a specification, reference being had therein to the accompanying drawings.

10 In the operation of automobiles, motor boats and the like, wherein the motor is liable to assume different inclined positions owing to the movement of the vehicle or boat, it is desirable for the feed pump of the lubricating system, if the latter be of the type 15 wherein the circulation system includes the engine base for trapping and returning the oil to the pump, that the oil be maintained at sufficient depth around the pump to always supply the latter regardless of the position of the motor.

This invention relates to a lubricating system for motors of automobiles, boats and the like wherein provision is made for maintaining 20 a supply of lubricant for a pump included in the system, regardless of the angle of inclination of the motor or its position under ordinary working condition.

The invention consists in the matters hereinafter set forth and more particularly pointed out in the appended claims.

In the drawings, Figure 1 is a plan view, partially broken away of the base of a motor, a feed pump and a gage tank that embody features of the invention; Fig. 2 is a view, partially in side elevation and partially broken away and in section of the base, tank and pump; Fig. 3 is a view in detail of a return check valve; Fig. 4 is a view taken 35 on or about line IV—IV of Fig. 1; Fig. 40 5 is a view taken in section on or about line V—V of Fig. 1; Fig. 6 is a view in end elevation of Fig. 1; Fig. 7 is an enlarged view, partially in longitudinal section and partially in elevation of a feed pump and driving mechanism therefor; Fig. 8 is a view in detail of the pump; and Fig. 9 is a view taken 45 on or about line IX—IX of Fig. 7.

As herein shown in preferred form, an engine base 1 suitably ribbed and flanged to combine strength and lightness is provided 50 at intervals with cross walls. These are

grooved, hollow or disposed in pairs, and form supports for the crank shaft bearings between which the cranks of the engine play. 55 A feed duct extends longitudinally of the base in substantially parallel relation to the upper, normally horizontal face thereof and through the pairs of cross walls. In preferred form, the duct is formed by a pipe indicated at 2, that is cast into the base when the latter is housed and is provided with a forward discharge aperture 3 that opens into the groove, hollow or space between the forward cross walls 4, another opening 5 60 that discharges into the space between another pair of cross walls 6, an aperture 7 between the cross walls 8, and an aperture 9 between the cross walls 10. The base, which is substantially semi-circular in cross section, 70 slopes downwardly from its forward end to its rear compartment in which the fly wheel turns. A combined gage reservoir and tank is seated on the dash or other convenient observation spot of the vehicle or boat on 75 which the motor is mounted and communicates with an inlet 11 of the pipe 2 through a suitable pipe 12 or the like, the reservoir being adapted to supply the inlet by gravity. In preferred form the tank comprised a 80 base 13 on which a bell jar 14 of glass or transparent material is secured as by a clamping rod 15 that may also hold a filling cap 16 in place. As one means of making connections between the pipe 12 and the inlet of the pipe 2, the pipe may have a flanged end 17 secured by a collar 18 on the nipple 19 of a fitting 20 detachably held against the side of the casing of the base by set screws 21 or the like. 90

A pump casing 22 is removably secured in the opening in the base near the lowest point thereof by cap screws 23 or the like. A foraminous cage 24 that acts as a screen to exclude dirt and like foreign substances 95 is formed on the casing around an inlet which supplies a chamber in which a pair of intermeshing gears 25 are secured. The follower gear rotates on a stud 26 or the like. The driving gear is keyed, splined or non-rotatably secured to an upright spindle 27 that is journaled in the cage through which it extends. A spiral spring 28 or other suitable driving connection connects the spindle 100

with a journal 29 that is mounted in a removable sleeve bearing 30 carried on the base and that is in turn operated through the medium of a gear 31 and worm 32. The 5 latter is connected to turn with the motor.

An outlet opening 33 in the pump casing discharges into a passage formed in the casing and connected by a pipe 34 with the gage reservoir. As a detail of construction, the 10 spindle 27 is provided with a head 35 that resists endwise movement and that corresponds to an enlarged portion 36 of the journal 29, the spring 28 being in compression between the heads. A suitably disposed 15 oil duct 37 sufficiently lubricates the bearing of the journal 29.

To prevent the escape of the oil from the space around the pump cage when the motor is tilted forwardly, and the oil approaches 20 the level indicated by the broken line 38 of Fig. 2, (suitable openings indicated at 39, in the forward cross walls, permitting this,) a swinging check valve is placed in an opening through the base of the walls 8, 8, this 25 opening being so disposed as to normally allow the oil to flow backwardly toward the pump chamber. Preferably the check valve consists of a closure 39 which hangs on a pivot pin 40 passing through a lug 41 extending from the closure, the parts being so disposed that the closure seats itself when the base is tilted forward slightly but opens to allow the backward flow of oil when the 30 level thereof ahead of the walls 8, 8 comes 35 higher than that of the lubricant accumulated in the chamber containing the pump gage. As a result of this construction any lubricant finding its way into the spaces between the bearing walls through the longitudinal and normally horizontal duct or 40 pipe, returns down the sloping wall of the base and collects in the chamber, around the gage of the pump and affords adequate supply to the latter under ordinary working 45 conditions. If the motor is tilted forwardly, the check valve prevents the corresponding movement of the oil and traps it so that it is retained in the base around and over the pump inlet.

50 Obviously, changes in the details of construction may be made without departing from the spirit of my invention and I do not care to limit myself to any particular form or arrangement of parts.

55 What I claim is:—

1. A lubricating system for a motor comprising a base provided with a longitudinally disposed feed duct and divided by cross walls between which the feed duct dis- 60 charges, the walls having openings whereby lubricant trapped in the base drains into the lowest compartment, an automatic check valve controlling the opening into the lowest

compartment for retaining the contents thereof when the base is tilted from normal 65 position, a pump having an inlet supplied by gravity from the lowest compartment, and a reservoir into which the pump discharges and from which the lubricant flows into the base feed duct. 70

2. In a lubricating system for a motor, an engine base having a longitudinally inclined bottom and cross walls dividing the base into compartments with drainage openings therethrough, a feed duct extending along 75 the wall of the base having outlets between the cross walls, an automatic check valve controlling the opening through a cross wall into the lowest compartment of the base for retaining the contents of said compartment 80 when the base is tilted from normal position, a pump having an inlet supplied from the lowest compartment, and a reservoir supplied by the pump and connected to the feed duct for supplying the latter. 85

3. In a lubricating system for a motor, a cast metal base provided with an inclined bottom and divided by cross walls into compartments with drainage openings through the walls, a substantially horizontal feed 90 duct pipe cast into the wall of the casing and provided with outlets into the base between the cross walls, an automatic check valve controlling the opening through a cross wall into the lowest compartment, a 95 pump having an inlet fed by gravity from the base compartment, and a reservoir supplied by the pump and connected to the feed duct pipe to discharge into the latter.

4. In a lubricating system for a motor, a 100 base having a longitudinally inclined bottom, cross walls dividing the base into compartments and having drainage openings therethrough, an automatic check valve in the drainage opening into the lowest compartment for retaining the contents of the latter when the base is tilted from normal position, a pump having an inlet supplied by gravity from the lowest compartment of the base and means for directing discharge 105 from the pump into the base compartments. 110

5. In a lubricating system for a motor comprising a base provided with a longitudinally inclined bottom and with cross walls dividing the base into compartments, the 115 cross walls having drainage openings therethrough, means controlling the opening into the lowest compartment for retaining the contents thereof when the base is tilted from normal position, a pump casing secured in 120 an opening in the base in the lowest compartment with an inlet opening from the compartment, a pair of intermeshing gears in the casing for forcing oil from the inlet to an outlet therefrom, means for returning 125 and distributing the discharge from the out-

let into the base compartment, a flexible driving connection for rotating one of the gears, and means for operating the connection from a motor.

5. 6. In a lubricating system for a motor, an engine base having a longitudinally inclined bottom, a pump casing secured in an opening in the bottom and provided with an inlet communicating with the interior of the 10 base, an upright spindle journaled in the pump casing, a pair of intermeshing gears mounted in the casing one of which is secured to the spindle, the gears being adapted to force liquid from the inlet of the casing 15 to an outlet, means for returning the discharge from the outlet to the engine base, a journal mounted in the engine base in substantially axial alinement with the spindle, a yielding driving connection between the 20 proximate end portions of the spindle and the journal, and means for rotating the journal by connection with a motor.

7. In a lubricating system for a motor, an engine base having a longitudinally inclined bottom, a pump casing secured in an opening in the bottom and provided with an inlet communicating with the interior of the base, an upright spindle journaled in the pump casing, a pair of intermeshing gears 30 mounted in the casing one of which is secured to the spindle, the gears being adapted to force liquid from the inlet of the casing to an outlet, a journal mounted in the engine base in substantially axial alinement 35 with the spindle, a yielding driving connection between the proximate end portions of the spindle and the journal, means for operatively connecting the journal to a motor, cross walls dividing the engine base into 40 compartments and having drainage openings therethrough, means for directing the discharge outlet into the compartments, and a check valve controlling the drainage opening into the compartment in communication 45 with the pump casing, adapted to retain the contents of said compartment when the base is tilted from normal position.

8. In a lubricating system for a motor, an engine base having a longitudinally inclined bottom, a pump casing secured in an opening in the bottom and provided with an inlet communicating with the interior of the base, an upright spindle journaled in the pump casing, a pair of intermeshing gears mounted in the casing one of which is secured to the spindle, the gears being adapted to force liquid from the inlet of the casing to an outlet, a journal mounted in the engine base in substantially axial alinement with the 55 spindle, a yielding driving connection between the proximate end portions of the spindle and the journal, means whereby the motor is adapted to drive the journal; cross

walls dividing the engine base into compartments and having drainage openings therethrough, a check valve controlling the drainage opening into the compartment in communication with the pump casing adapted to retain the contents of said compartment when the base is tilted from normal position, a normally horizontal feed duct in the base having outlets discharging into the various compartments of the latter, and a slight feed reservoir connected with the outlet of the pump and arranged to discharge into the 75 feed duct.

9. In a lubricating system for a motor, an engine base having a longitudinally inclined bottom, cross walls dividing the base into compartments and having drainage 80 openings therethrough, means controlling the opening into the lowest compartment for retaining the contents thereof when the base is tilted from normal position, a pump casing secured in an opening in the bottom 85 of the base in the lowest compartment with an inlet in communication with said compartment, rotatable forcing members in the pump casing for driving lubricant from the inlet through an outlet of the pump casing, 90 driving mechanism in the base for operating the pump from a motor, a sight feed reservoir into which the pump discharges, a feed duct pipe secured in the wall of the base and provided with discharge openings between the cross walls of the base, and a pipe 95 connecting the reservoir with the duct pipe.

10. In a lubricating system for a motor, a base provided with a longitudinally inclined bottom and divided by cross walls into compartments in communication through drainage openings in the cross walls, means controlling the opening in the cross wall into the lowest compartment of the base for retaining the contents of the latter when the 100 base is tilted from normal position, a pump casing secured in an opening in the bottom of the lowest compartment, provided with an inlet fed by gravity from the compartment, a foraminous cage shielding the inlet, 110 a pair of intermeshing gears in the pump casing adapted to force lubricant supplied by the inlet through an outlet from the casing, means for directing the discharge from the outlet to the base compartments, a spindle journaled in the casing on which one of the gears is secured, a sleeve bearing secured on the base, a journal rotatable in the bearing, a spring member operatively connecting the proximate end portions of the spindle 120 and journal adapted to prevent end play in both and to rotate them substantially in unison, and means for driving the journal from the motor.

11. A lubricating system for a motor comprising an engine base divided by cross

walls that have drain openings therethrough whereby lubricant in the base drains into the lowest compartment thereof, means for retaining the contents of the lowest compartment when the base is tilted from normal position, a feed duct at one side of the base having discharge openings into the base between the cross-walls, and means for forc-

ing lubricant from the lowest compartment into the feed duct.

In testimony whereof I affix my signature in presence of two witnesses.
